UNITED STATES PATENT OFFICE.

SOPHIA L. CROWNFIELD, OF NEW YORK, N. Y., ASSIGNOR TO CHENEY BROTHERS, OF SOUTH MANCHESTER, CONNECTICUT, A CORPORATION OF CONNECTICUT.

DESIGN FOR TEXTILE FABRIC.

40,898.

Specification for Design. Patented Sept. 20, 1910.

Application filed May 13, 1910. Serial No. 561,268. Term of patent 3½ years.

To all whom it may concern:

Be it known that I, SOPHIA L. CROWNFIELD, a citizen of the United States, residing in the borough of Manhattan, city, county, and State of New York, have invented a new, original, and ornamental Design for Textile Fabrics, of which the following is a specification, reference being had to the accompanying drawing, forming part thereof.

The drawing illustrates a section or portion of a fabric embodying my new design.

I claim:

The ornamental design for a textile fabric, as shown.

SOPHIA L. CROWNFIELD.

Witnesses:

MARY DUTTON,
L. F. BROWNING.
